UNITED STATES PATENT OFFICE.

CHARLES S. CUSHMAN, OF BARRE, VERMONT.

MAGNETIC HEATER.

1,307,773.

Specification of Letters Patent. Patented June 24, 1919.

Application filed May 31, 1918. Serial No. 237,560.

To all whom it may concern:

Be it known that I, CHARLES S. CUSHMAN, a citizen of the United States, residing at Barre, in the county of Washington, State 5 of Vermont, have invented certain new and useful Improvements in Magnetic Heaters; and I do hereby declare the following to be a full, clear, and exact description of the invention, such as will enable others skilled 10 in the art to which it appertains to make and use the same.

The present invention relates to new and useful improvements in electrical heating devices more particularly of that type utilizing 15 heat generated in the core of an electromagnet through which an alternating current is passed.

It is in general the object of the present invention to improve the structure and increase 20 the heating efficiency of devices of this character, and it is more particularly the object to provide a most effective device for heating water, compressed air, or other confined fluid during its passage through a 25 pipe line.

A further object resides in the provision of an arrangement wherein the number of heating units employed may be readily varied, to thus vary the amount of heat supplied. 30

A still further object resides in the provision of an arrangement embodying a heating magnet core wherein a secondary circuit is set up within the core to afford a heating 35 thereof additional to the heat generated by magnetic fluctuations of the core.

With the above and other objects and advantages in view, the invention resides more particularly in the novel combination, formation and arrangement of parts herein-after described and particularly pointed out in the appended claims.

In the drawings:

Figure 1 is a side elevational view of a 45 magnetic heater embodying the present invention.

Fig. 2 is a sectional view therethrough showing one of the heating elements in plan.

Fig. 3 is a transverse sectional view 50 through the device longitudinally of one of the heating elements, on the line 3-3 of Fig. 1.

Fig. 4 is a transverse sectional view 55 through one of the heating elements.

Referring now more particularly to the accompanying drawings, the body frame of

the device is formed of a section of pipe line, essentially of U-shape, and comprising the parallel side pipes 5 connected at adjacent ends by elbows 6 with a short pipe 60 section 7 forming the bight of the U. The other end of one of the pipes 5 is provided with an attaching elbow 8, and the corresponding end of the other pipe 5 is provided with a T-coupling 9 for connection with the main pipe line and with a suitable drain pipe 10. These last named ends of the pipes 5 are held against spreading by a suitable tie member 11.

Any number of heating elements may be 70 associated with the side pipes 5 to impart varying degrees of heat to fluid contained in the pipes, and in the present instance three heating units are employed. Each of these heating units comprises a magnetic core 75 formed of a pair of sections 12 held in spaced position and insulated by transverse bars 13 disposed therebetween, and wound about each core is a magnetic coil 14. Each of the core sections is formed of a series of 80 plates, which are successively increased in length toward the outer side of the section, the innermost plates being of a length substantially equal to the distance between the adjacent peripheral portions of the pipes 5. 85 When the cores are disposed between the pipes, the end portions of their laminations engage the peripheral surfaces of the pipes, the entire core thus presenting concave end faces of substantially semi-circular curvature whereby the adjacent portions of the pipe form the outer extremities of the core. The laminations of the core sections are firmly clamped against the pipes by clamping bolts 15 passed transversely through the 90 plates.

Thus upon passing alternating current 95 through the coils 14, magnetic fluctuations will be set up within the cores, to heat said cores, the heating action being strongest at the ends of the cores and thus imparting heat directly and in a most efficient manner to the fluid contained within the pipes.

It will be noted that the complete heater is in effect a transformer of which the coils 105 14 constitute the primary element while the pipe constitutes the secondary element in addition to forming a part of the magnetic circuit. In use, the secondary element is allowed to run hot while the primary is run 110 at a safe temperature for the insulating material. Thus, there is utilized in the heating

of the fluid in the pipe, both the secondary current and the resultant of the rapid reversals of magnetic polarity, it being understood that the apparatus is used in connection with alternating current, for highest efficiency.

What is claimed is:

1. A heater comprising a U-shaped body frame formed of pipe sections, a plurality of cores extending transversely between and having their ends connected with the sides of said frame and electric conducting coils wound on said cores.
- 10 2. A heater comprising a pair of parallel pipe sections, a magnet core formed of strips successively increased in length toward the outer sides of the core whereby to define concave end faces for the core body and

engaging the peripheral surfaces of the pipes, and an electric conducting coil wound about said core.

- 15 3. A heater comprising a pair of parallel pipe sections, a pair of spaced core sections each formed of a series of plates successively increased in length toward the outer sides of the sections, clamping bolts passed through the plates of the sections for clamping the ends of said plates against the peripheral surfaces of the pipes and an electric conducting coil wound on said core.

In testimony whereof, I affix my signature, in the presence of two witnesses.

CHARLES S. CUSHMAN.
